UNITED STATES PATENT OFFICE.

JULIAN A. RAMSEY, OF WASHINGTON, PENNSYLVANIA, ASSIGNOR, BY DIRECT AND MESNE ASSIGNMENTS, TO EASTMAN KODAK COMPANY, OF ROCHESTER, NEW YORK, A CORPORATION OF NEW YORK.

PHOTOGRAPHIC PRINTER.

Application filed June 28, 1921. Serial No. 481,071.

To all whom it may concern:

Be it known that I, JULIAN A. RAMSEY, a citizen of the United States, residing at Washington, in the county of Washington and State of Pennsylvania, have invented certain new and useful Improvements in Photographic Printers, of which the following is a full, clear, and concise description thereof.

10 One object of the invention is to provide a power-operated photographic printer, each movement of which is under the voluntary control of the operator. Another object of the invention is to provide a printer, the 15 working forces for which are supplied by a source of power instead of by the operator, thereby relieving the latter from fatigue and increasing the output, each movement of the printer taking place upon 20 a simple actuation of a control means by the operator. Still another object of the invention is to provide a printer of this character which is fluid operated. A further object of the invention is to include in 25 the printer means for storing energy in a simple manner, so that the operator can release the energy at will to move the platen. Another object of the invention is to automatically time the operations of a light and 30 of a paper-ejector in a printer of this character.

Other objects and advantages of the invention will be apparent from the following description when taken in connection 35 with the accompanying drawings, in which:

Figure 1 is a side elevation of the printer.

Figure 2 is a longitudinal section through the cylinder thereof.

Figure 3 is a longitudinal section through 40 the valve.

Figure 4 is a front elevation of the entire device.

Figure 5 is a horizontal section through the upper portion of Fig. 1.

Figure 6 is a section through the print 45 lifter; and

Figure 7 is a perspective view of a modified form of printer.

Referring to the drawings more in detail, the numeral 1 designates the stand or frame of the printer, to the top 2 of which is secured the arm or support 3 for the cylinder 4. In the cylinder 4 is located the piston 5 and piston rod 6 in the usual man-

ner. The crosshead 7 is secured to the 55 lower end of rod 6, and is slideable on the rods 8 which are secured to the upper face of the lid 9. Springs 10 surround the rods 8 and of course are interposed between the crosshead 7 and the lid or platen 9. The 60 lower face of the lid 9 carries a felt pad 11 which makes a soft and even contact between the sensitized paper and the negative, when the platen 9 is down in its lower or 65 printing position.

A tank 12 is supported in the lower portion of the stand 1, and in this tank is stored air or other fluid by means of the motor 13 and pump 14. Leading from the tank 12 is a pipe 15 which carries the fluid to the 70 valve cylinder 16. Valves 17 in the cylinder 16 are carried by rod 18 and are normally held in the position shown in Fig. 3 by means of the spring 19. Connected near the top and bottom of the valve cylinder 16 are the conduits or pipes 20 and 21 leading to the top and bottom respectively of the cylinder 4. By moving the valve 17, by pressure applied through the hand or any other part of the operator to its lower 75 position the operating fluid is admitted to the top of cylinder 4 and lowers the lid 9, while on releasing the valve the spring 19 moves the same to its normal position shown in Fig. 3 and admits the fluid to the lower 80 portion of cylinder 4 and raises the platen 9 to its clearance position. When the valve 17 is in the position shown in Fig. 3, the exhaust air from the top of cylinder 14 85 escapes through pipe 20 and apertures 20 in the bottom of the valve cylinder 16 to the atmosphere. In the reverse position of valve 17, the exhaust air from the bottom of the cylinder 14 escapes through pipe 21 and the open top of the valve cylinder 16. 90

To prevent the crosshead and related parts from turning, I have provided the crosshead with an extension guide arm 22, which is notched at 23 so as to straddle and slide on the bracket arm 3. Attached to the arm 22 is a fibre insulator 24 which carries a contact screw 25. The contact 95 makes connection across the switch bars 26 which are mounted on the fibre insulator 27. The switch bars 26 are in circuit with the lamps in lamp box 28 which is supported on frame 1 under the top 2 thereof the latter comprising the printing panel customary in 100 105

this art. The switches 29 are connected in series with the switch bars 26 and provide means whereby one or more of the lamps may be used as required.

- 5 For the purpose of presenting the print in proper position for easy removal from the machine, I have provided the vacuum cup 30 mounted on the lower end of rod 31. This rod 31 is positioned in the cylinder 10 32 which is carried by the lid 9. A spring 33 in cylinder 32 holds rod 31 and vacuum cup 30 normally in the position shown in Fig. 6. As the lid is lowered the spring 33 is compressed and the vacuum cup 15 30 pressed against the sensitized paper. On raising the lid 9 the cup picks up the print and the spring 33 moves the cup downward relatively to the lid and thereby presents the print for removal.
- 20 A mask 34 is provided for regulating the size of the print. This mask is fastened to the inside of the frame 1 which exposes only the leaves of the mask, which latter designate the size of print for which they 25 are adjustable. The mask is operated by means of the knobs 35. A knob 36 is provided for the purpose of tilting the bottom (not shown) of the lamp box to which the lamp sockets are attached, for the purpose 30 of bringing the lamps nearer to certain portions of the negative.

A numbering machine 37 is operated by the crosshead 7 on each downward movement of the lid 9.

- 35 In the modified form shown in Fig. 7 the same reference numerals are used to designate parts which are the same as those already described in connection with the foregoing embodiment of the invention. In this 40 form the crosshead 7 is guided in the frame members 40, and instead of being operated by fluid pressure is operated by means of a pressure is operated by means of a treadle 41 to which is connected by means 45 of cross-rod 42 the upright connecting rods 43. Between the nuts 44 on the upper ends of rods 43 and the crosshead 7 are interposed the springs 45. Weights 46 are also connected to treadle 41 through chains 47 50 and the cross-rod 42. By means of the weights 46 the treadle 41 is raised and likewise the lid 9 when the foot of the operator is removed from the treadle.

A frame screen 48 operable by knob 49 55 is provided for dimming the lights when necessary. This is done by means of sheets of tissue paper laid upon the screen 48.

Numeral 50 indicates a switch for operating the pilot light used in connection with the large types of machines.

In accordance with the patent statutes I have described what I now believe to be the best embodiment of the invention, but I do not wish to be understood thereby as limiting myself or the scope of the invention, as

many changes and modifications may be made without departing from the spirit of the invention, and all such I aim to include in the scope of the appended claims.

What I claim as new and desire to secure 70 by Letters Patent is:

1. A printer including a lamp box, a lid mounted for movement toward and from said lamp box, and means connected with the lid for moving the article printed to a 75 position spaced from the lid and holding the same in such position until manually removed.

2. In a printer, a frame, a lamp box there- 80 in, a lid for said lamp box, means for operat- ing said lid, said means including a piston rod and crosshead therefor, rods extending from said lid through the crosshead, and springs interposed between the crosshead and lid.

3. A photographic printing machine, comprising a printing panel, a platen movable into printing position on said panel and removable from said panel to clearance position to permit manual access to the space between it and the panel, means, including a source of motive power, for moving said platen to printing position, holding it in such position, and removing it to clearance position, a control member the actua- 90 tions of which are manually governed and connections between said member and said means which govern the means to move said platen to printing position upon manual actuation of the control member, to remove said platen to clearance position upon further actuation of said member, and to retain said platen in printing position between said actuations.

4. A photographic printing machine com- 100 prising a printing panel, a platen movable into printing position on said panel and from said panel to clearance position, means, including a power device, for moving said platen to printing position, holding it in said position, and removing it to clearance position, means for storing energy for actuating said device, means for directing en- 110 ergy from said storing means to said device, and control means, the actuations of which are governed by the operator, said control means including an element which regulates the passage of energy from said storing means to said power device, and said control means, upon successive actuations by the operator, governing said first-named means to move the platen to said printing position, retain it during the will of the operator in said position, and remove it to clearance position.

5. A photographic printing machine, comprising a printing panel, a platen movable into printing position on said panel and from said panel to clearance position, means including a source of power, for moving said 120

- platen to printing position, holding it in said position, and removing it to clearance position, an ejector for removing the printed sheet from printing position upon movement of the platen to said clearance position, and control means, which is connected to said first named means, and the actuations of which are governed by the operator, said control means, upon successive actuations by the operator, governing said first named means to move the platen to said printing position, retain it during the will of the operator in said position, and remove it to clearance position.
6. A photographic printer, comprising a printing panel, a lighting unit for sending printing light through said panel, including a device for starting and stopping said sending of said light, a platen movable into printing position on said panel and from said panel to clearance position, means, including a source of power, for moving said platen to printing position, actuating said device to start said sending of the light, holding said platen in printing position, actuating said device to stop said sending of the light, and removing said platen to clearance position, and control means, which is connected with said first-named means, and the actuations of which are governed by the operator, said control means, upon successive actuations, governing said first-named means to move the platen to said printing position and start said sending of light, retain said platen in said printing position and continue said sending of light during the will of the operator, and stop said sending of light and remove said platen to clearance position.
7. A photographic printing machine, comprising a printing panel, a platen movable into printing position on said panel and removable from said panel to clearance position to permit manual access to the space between it and the panel, means, including a fluid operated source of motive power, for moving said platen to printing position, holding it in such position, and removing it to clearance position, a control member the actuations of which are manually governed and connections between said member and said means which govern the means to move said platen to printing position upon manual actuation of the control member, to remove said platen to clearance position upon further actuation of said member, and to retain said platen in printing position between said actuations.
8. A photographic printer, comprising a printing panel, a platen movable into printing position on said panel and from said panel to clearance position, means, including a source of power, for moving said platen to printing position, holding it in said position, and removing it to clearance position, and control means, which is connected to said first named means, and the actuations of which are governed by the operator, said control means upon successive actuations by the operator governing said first named means to move the platen to said printing position, retain it during the will of the operator in said position, and remove it to clearance position.
9. A photographic printing machine, comprising a printing panel, a platen movable into printing position on said panel and removable from said panel to clearance position to permit manual access to the space between it and the panel; means, including a source of motive power, for moving said platen to printing position, holding it therein, and removing it to clearance position, a control member movable to different positions, the movements of which are manually governed, and connections between said member and said means which govern said means first to move the platen to printing position when said member is manually moved to one of its positions, then to retain said platen in printing position while the member remains in said one position, and then to remove said platen to clearance position when said member is moved to a different position.
10. A photographic printing machine, comprising a printing panel, a platen movable into printing position on said panel and removable from said panel to clearance position to permit manual access to the space between it and the panel; means, including a fluid operated source of motive power, for moving said platen to printing position, holding it therein, and removing it to clearance position, a control member movable to different positions, the movements of which are manually governed, and connections between said member and said means which govern said means first to move the platen to printing position when said member is manually moved to one of its positions, then to retain said platen in printing position while the member remains in said one position, and then to remove said platen to clearance position when said member is moved to a different position.

JULIAN A. RAMSEY.
